SAMUEL CARMIN, OF SYRACUSE, NEW YORK

WINDOW-FRAME CONSTRUCTION

Application filed August 22, 1928. Serial No. 301,377.

This invention relates to a window frame having a displaceable jamb section to permit the removal of the lower and upper sash without displacing any of the stops.

5 The main object is to yieldingly support the displaceable jamb section in such manner that it may be sprung laterally into the sash weight housing a sufficient distance to permit the sash to be moved endwise into the opening formed by such displacement for withdrawing its opposite side from between the stops and parting strips and then moved inwardly and laterally in a reverse direction thereby displacing the sash from the frame.

10 15 In other words, I have sought to support the displaceable jamb section by means of a looped spring having its upper end secured to the overlying portion of the jamb and its lower end provided with a vertically elongated loop adapted to interlock with a staple on the adjacent upper end of the movable jamb section whereby said section may be displaced outwardly and laterally against the action of the spring and then moved downwardly until limited by the engagement of the staple with the lower end of the loop thereby affording ample clearance for receiving the adjacent edge of the sash when removing the same from the window frame.

20 25 30 Another object is to provide metallic anchorage for the sash cord for insertion into the sockets of the opposite side edges of the sash.

35 Other objects and uses will be brought out in the following description.

In the drawings:

Figure 1 is an inner face view, partly in section of one side of the window frame and adjacent side of the lower and upper sash.

40 Figures 2 and 3 are vertical sectional views taken in the planes of line 2—2 and 3—3, Figure 1.

Figure 4 is a horizontal sectional view taken in the plane of line 4—4, Figure 1.

45 Figure 5 is a perspective view of the upper corner of the lower sash and one of the sash cords detached therefrom showing more particularly the construction of the cord anchorage.

50 Figure 6 is an enlarged horizontal sectional

view through the movable jamb section taken in the plane of line 6—6, Figure 3.

As illustrated, in order that the invention may be clearly understood I have shown a portion of a window frame —1— and portions of the lower and upper sash —2— and —3—. The frame —1— is provided with the usual sill —4— and upright cases —5— for receiving the sash weights, not shown, except that a portion —6— of one of the jambs for the lower sash is displaceable outwardly to form an opening —6'— through which the lower and upper sash —2— and —3— may be moved laterally a limited distance sufficient to withdraw their opposite sides from engagement with the adjacent stops.

For example, one of the upright window casings, in this instance, the one at the right hand of Figure 4 is provided with the usual sash guides formed by jambs —7— and —7'—, inner and outer stops —8— and —8'— and a parting strip —9—.

The other or left hand casing, Figure 4, is provided with the usual jamb —7"— for the upper sash —3— similar to the jamb —7'— in that it extends continuously from top to bottom of the window frame while the adjacent jamb for the inner sash —2— is provided with the opening —6'— extending from the inner face of the inner stop —10— to the inner face of the parting strip —9'— and also extending from a horizontal plane a short distance above the sill —4— to a height somewhat greater than the vertical height of the sash —2— and —3—, said opening being normally filled by the jamb section —6— to form a continuation of the adjacent relatively fixed lower and upper jamb sections —11— and —11'—.

The parting strip —9'— is formed integral with or united to the jamb section —6— for displacement therewith from its normal position into the adjacent casing —1— to permit the sash —2— and —3— to be displaced laterally through the opening —6'— a sufficient distance to withdraw the opposite upright edge of the sash from between the stop —8— and parting strip —9— after which the right hand edge of the sash may be drawn to the position shown by dotted

lines in Figure 4 and then drawn laterally to the right to withdraw the same from the opening —6'— thus completing the removal of the lower sash.

5 In like manner, when the jamb section —6— is displaced inwardly into the adjacent casing —1— as shown by dotted lines in Figure 4 the upper sash may be lowered to the level of the opening —6'— and its left hand drawn forwardly into registration with said opening and then moved laterally thereinto to withdraw its opposite upright edge from between the parting strip —9— and stop —8'— whereupon the right hand upper edge of the sash —3— may be drawn inwardly to about the position shown by dotted lines in Figure 4 thus permitting the sash —3— to be withdrawn laterally to the right hand of Figure 4 from the opening —6'—.

20 The lower end of the movable jamb section —6— and adjacent upper edge of the fixed jamb section —11— are rabbeted transversely to form flanges —12— and —12'— adapted to overlap upon each other when the jamb section —6— is in operative position.

25 In like manner the upper end of the jamb section —6— and adjacent lower edge of the fixed jamb section —11'— are rabbeted transversely to form inner and outer flanges —13— and —13'— adapted to overlap upon each other when the section —6— is in operative position.

30 As illustrated, the flange —12— overlaps upon the outer face of the flange —12'— to permit the lower end of the section —6— to be displaced outwardly into the adjacent upright portion of the casing while the upper flange —13— overlaps upon the inner face of the flange —13'— to prevent outward displacement of the upper end of the section —6— until the lower end of said section has been moved outwardly and downwardly as shown by dotted lines in Figure 1.

35 The jamb section —6— is yieldingly held in its operative position by means of a flat spring —14— having its upper end widened and secured by screws —15— to the outer face of the lower end of the upper fixed jamb section —11'—, the lower end of said spring being extended downwardly along the outer face of the section —6— some distance below the upper end thereof and returned inwardly and outwardly to form a loop —14'— having its inner end slidably locked with a 40 staple —15— which is secured to the adjacent portion of the section —6—.

45 The inner end of the loop —14'— extends above and below the staple —15— when the section —6— is in its operative position and 50 extends downwardly a distance below the staple somewhat greater than the vertical width of the flanges —13— and —13'— to permit the entire disengagement of the upper end of the section —6— with the fixed section —11'— when the lower end of said section is

55 disengaged from the fixed jamb section —11— thus permitting the entire section —6— to be moved outwardly against the action of the spring —14— or a sufficient distance to permit either sash to be moved through the opening —6'— and then withdrawn laterally from the opening as shown by dotted lines in Figure 4.

60 For example, when the lower end of the section —6— is displaced from the fixed section —11— it drops by its own weight along the 65 loop —14'— until limited by the engagement of the staple —15— with the lower end of the loop.

70 Suitable means is provided for holding the lower end of the section —6— against outward displacement when in its operative position and for this purpose a screw —16— is secured to the inner face of the lower end of the section —6— and is provided with an eccentric head —16'— movable into and out of 75 engagement with the inner face of the adjacent end of the fixed jamb section —11— as shown more clearly in Figure 2.

Operation

80 When it is desired to move either sash —2— or —3— the screw —16— will be operated by a suitable driver to bring its eccentric portion —16'— out of interlocking engagement with the jamb section —11— whereupon the section —6— is moved inwardly and drops downwardly until limited by the engagement of the staple —15— with the lower end of the loop —14'—.

85 Either sash is then adjusted to register its 100 left hand side with the openings —6'—, the sash registering with the opening —6'— may then be moved endwise into said opening a sufficient distance to withdraw its opposite sides from engagement with the stops —8— and —9— at which time the right hand sash may be pulled outwardly to the position shown by dotted lines in Figure 4 and then moved laterally toward the right hand until withdrawn from the opening —6'—.

90 By reversing these movements of the sash it may be restored to its operative position and moved upwardly a sufficient distance to permit the section —6— to be restored to its 105 operative position by hand and locked in place by the screw —16—.

95 It is understood, of course, that when the sash are brought into registration with the opening —6'— the sash weights attached in the usual manner to cords —a—, Figures 1 110 and 5, will be drawn upwardly out of the path of movement of the jamb section —6— to permit the latter to be readily displaced outwardly.

100 The inner end of the cord —a— is provided with a cylindrical anchor adapted to enter a corresponding socket —a'— in the upper portion of the outer edge of the sash which is also provided with a groove —a'— extending 115

upwardly from the socket —a'— to receive the cord.

The anchor —a— may be made of sheet metal or of cast metal as may be desired for strength and durability but is hollow so that the end of the cord may be carried in a knot and inserted therein after passing the end of the cord through an opening —A'— in the upper side thereof, the outer end as —b— of the anchor being closed and substantially smooth to register with the outer edge of the sash —2— when the anchor is inserted in the socket —a'—.

What I claim is:

15 A frame for window sash, a window jamb having an opening therein of sufficient size to permit the adjacent portion of the sash to pass edgewise therethrough, a jamb section normally filling said opening and displaceable 20 outwardly therefrom, a leaf spring having its upper end secured to a fixed portion of the jamb above said opening and its lower end spring pressed against the outer face of the movable jamb section and returned upwardly 25 to form a loop open at the top and means on the movable jamb section slidably engaged in said loop to permit the jamb section to be removed by upward displacement from the loop.

In witness whereof I have hereunto set my 30 hand this 14 day of August, 1928.

SAMUEL CARMIN.
